UNITED STATES PATENT OFFICE.

EDWARD H. ASHCROFT, OF LYNN, MASSACHUSETTS.

STEAM-BOILER.

SPECIFICATION forming part of Letters Patent No. 240,219, dated April 19, 1881.

Application filed February 26, 1881. (No model.)

To all whom it may concern:

Be it known that I, EDWARD H. ASHCROFT, a citizen of the United States, residing at Lynn, in the county of Essex and State of Massachusetts, have invented a new and useful Improvement in Steam-Boilers; and I do hereby declare that the following is a full, clear, and exact description thereof, reference being had to the accompanying drawings, forming a part 10 of this specification, in which—

Figure 1 is an elevation, partly in section; Fig. 2, a plan view of the central nozzle; Fig. 3, a plan view of an end nozzle when applied as represented in Fig. 1; and Fig. 4 an elevation, partly in section, of a modified arrangement of my invention.

Similar letters of reference indicate corresponding parts in the several figures.

This invention relates to steam-boilers of the 20 compound type which are composed of two parts, one containing the internal tubes or flues and constituting the principal generator, and the other or auxiliary part serving as the water and steam chamber from which the supply of steam is drawn. These respective parts are usually constructed of independent cylindrical shells, arranged one above the other and connected together by intermediate nozzles, which form communicating passages, the auxiliary part being placed above the generator and covered with a hood, within which the escaping products of combustion are contained, which prevents a loss of heat by radiation and also superheats the steam.

In the construction of this type of boiler it has been found difficult to apply the intermediate nozzles particularly at the extreme ends of the respective shells, where it is desirable to place the opening or passage as near as possible to insure unobstructed circulation. Heretofore these nozzles have been formed by turning up or flanging a part of the plate of each shell, and lapping and riveting the same together. This expedient not only necessitated an abrupt bending of the plates, but in forming a flange-connection with the ends or heads in contact unshapely bends and unsightly seams were presented.

The object of this invention is to overcome 50 this difficulty, and also to provide in the construction of the nozzles means for retaining a

part of the water in the auxiliary chamber at all times, all as hereinafter particularly described and claimed.

In the drawings, *a* represents the main portion of the boiler, and *b* the auxiliary water and steam chamber.

c c' are the connecting-nozzles, which embody my invention. These nozzles, owing to their limited length, are necessarily of such 60 shape to conform to the adjacent parts that it is deemed preferable to construct them of cast metal, thereby lessening the cost of manufacture, securing greater strength, in the more rigid support, and in avoiding the weakening 65 effect in the bending and fitting of wrought-plates.

The nozzle *c*, which is designed to be used at the middle portion of the boiler, is composed of a central tube, *d*, forming the passage, which 70 is fitted within circular openings in the shells of the respective parts, the bottom or lower end of said tube being flush with the interior surface of the shell, and the upper end extending beyond the interior surface of the shell of 75 the auxiliary chamber, whereby an amount of water in depth equal to the distance said tube extends within the chamber will be retained therein, the projecting tube not permitting a return of all the water when the level falls below the chamber. This tube is provided with circumferential flanges *e*, formed to fit the exterior shape of the respective shell, and to which they are secured by riveting or in any well-known way. One or more of these intermediate nozzles may be used, as judgment may 85 dictate, to accommodate boilers of varying length, or to increase or diminish the capacity of the aggregate passages.

The nozzles *c'*, which are placed at the extreme ends of the respective parts, are essentially the same as a half-section of the intermediate nozzles, *c*, the flat side being arranged in contact with the end or head, and slots provided between the central tube and the exterior projecting flanges to receive the end flanges, this construction forming an uninterrupted connection or seam and securing the open passage at the extreme end of the boiler, whereby no obstruction is interposed to the 100 free circulation at this point.

In a modification of this invention, Fig. 4, I

have shown the complete circular nozzles located as near the ends as it may be found convenient and practical, and supplementary tubes *h* inserted between the same and the extreme ends of the boiler, whereby the same result may, in a measure, be accomplished, this modification being also adapted to a construction in which the respective heads of each part of the boiler are made in separate and distinct parts, the first-described construction permitting the head to cover each part to be applied in a single plate.

The advantages resulting from this construction are manifestly superior in regard to strength, durability, and appearance when compared with the use of wrought plates, and the cost of manufacture is greatly reduced.

Having thus fully described my invention, what I claim, and desire to secure by Letters Patent, is—

In a compound boiler having a series of intermediate necks or nozzles for connecting the main and auxiliary parts thereof and forming communicating passages, the end or extreme nozzles, *c'*, constructed in cross-section with a plane vertical surface adjacent to the boiler-head, and connected thereto and to the respective shells, substantially as shown and described.

EDWARD H. ASHCROFT.
